(57) CLAIM

The ornamental design for a television monitor, as shown and described.

DESCRIPTION

FIG. 1 is a perspective view of a television monitor showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof showing the state in which the television monitor has been installed to a wall after the stand part has been detached.

The broken lines shown in FIG. 8 are for illustrative purposes only and form no part of the claimed design.
